Primary Examiner—Prabhakar G. Deshmukh*Assistant Examiner*—Catherine Tuttle*Attorney, Agent, or Firm*—Kenneth A. Roddy[57] **CLAIM**

The ornamental design for a visor for caps, as shown and described.

DESCRIPTION

FIG. 1 is a perspective view of a visor for caps showing my new design;

FIG. 2 is a top plan view thereof;

FIG. 3 is a bottom plan view thereof;

FIG. 4 is a right side view thereof; and,

FIG. 5 is a left side view thereof, the broken line showing the cap in the figures is for illustrative purposes only and forms no part of the claimed design and the striping represents a contract in color and texture.
